Primary Examiner — Jonathan J Han(74) *Attorney, Agent, or Firm* — Snell & Wilmer L.L.P.(57) **CLAIM**

The ornamental design for a sole for a shoe, as shown and described.

DESCRIPTION

FIG. 1 is a top, rear and outer-side isometric view of a sole for a shoe.

FIG. 2 is a front view of the sole of FIG. 1.

FIG. 3 is a rear view of the sole of FIG. 1.

FIG. 4 is an inner-side view of the sole of FIG. 1.

FIG. 5 is an outer-side view of the sole of FIG. 1.

FIG. 6 is a top view of the sole of FIG. 1.

FIG. 7 is a bottom view of the sole of FIG. 1.

FIG. 8 is a bottom, rear and inner-side isometric view of the sole of FIG. 1.

FIG. 9 is a cross-sectional view of the sole taken along line 9-9 of FIG. 6.

FIG. 10 is a cross-sectional view of the sole taken along line 10-10 of FIG. 6.

FIG. 11 is a cross-sectional view of the sole taken along line 11-11 of FIG. 6; and,

FIG. 12 is a cross-sectional view of the sole taken along line 12-12 of FIG. 6.
